UNITED STATES PATENT OFFICE.

GUSTAV CHRISTIAN NUESSE, OF HIBBING, MINNESOTA.

LOADER.

1,416,118.

Specification of Letters Patent. Patented May 16, 1922.

Application filed April 25, 1921. Serial No. 464,071.

To all whom it may concern:

Be it known that I, GUSTAV C. NUESSE, a citizen of the United States, residing at Hibbing, in the county of St. Louis and State of Minnesota, have invented certain new and useful Improvements in Loaders; and I do declare the following to be a full, clear, and exact description of the invention, such as will enable others skilled in the art 10 to which it appertains to make and use the same.

My invention relates to devices for loading and unloading purposes and has for its object to provide an extremely simple and 15 inexpensive, yet a highly efficient, easily operated and rapid device which may be operated by one man, for instance for loading and unloading cars.

In the accompanying drawings, forming 20 a part of this specification;

Figure 1 is a side elevation of a loader constructed in accordance with my invention.

Figure 2 is a front end elevation.

Figure 3 is a vertical sectional view with parts in elevation.

Figure 4 is an enlarged sectional view through the upper and lower ends of the vertical standard, and associated parts.

Figure 5 is an elevation, partly in section of the standard and its clamping means.

Figure 6 is a horizontal sectional view as indicated by line 6—6 of Fig. 3.

Figure 7 is a detail vertical section as indicated by line 7—7 of Fig. 6.

In the drawings above briefly described, the numeral 1 designates a vertically disposed cylindrical standard having threaded bores 2 in its upper and lower ends, into 40 which screws 3 are threaded, the outer ends of said screws being provided with plates 4 which are preferably swiveled thereto as indicated at 5. The screws 3 are provided with appropriate handles 6 whereby they 45 may be rotated to force the plates 4 against the floor and ceiling of a car, a mine, or the like.

Rotatably surrounding the standard 1, is a sleeve 7 whose lower end is here shown 50 resting on ball-bearings 8 supported by an outstanding flange 9 on said standard, while roller-bearings 10 are illustrated between the upper ends of said standard and sleeve. By mounting the sleeve in the manner dis- 55 closed or in a similar manner, it may be turned freely upon the standard 1 and for

so turning said sleeve, I provide the latter with a horizontally extending handle 11. As shown, this handle is provided with a spring-pressed latch rod 12 which extends 60 through an opening 13 in the sleeve 7 for engagement with any one of a plurality of sockets 14 with which the standard 1 is provided. It will thus be seen that when sleeve 7 is once turned, it may be locked against 65 further movement.

At its lower end, the sleeve 7 is provided with an outwardly extending vertical flange 15 to which a pair of inclined brace bars 16 are secured, the upper ends of said brace 70 bars being spaced outwardly from the sleeve 7 and tied to the latter by appropriate tie bars 17. In the angle between the brace bars 16 and the sleeve 7, a horizontal motor support 18 is mounted and said brace bars 75 preferably diverge sufficiently to straddle said support as shown in Fig. 2 thereby forming an effective brace and holding means for the outer end of said support, the inner end of the latter being appropriately 80 secured to the sleeve.

A telescopic boom 19 is pivoted at 20 to the sleeve 7 and is positioned to swing vertically between the brace bars 16, said boom being preferably formed of a tubular section 85 21 which is pivotally mounted and another section 22 sliding in said tubular section and carrying an appropriate bucket 23. By adjusting the section 22 within the section 21, the length of the boom may be increased or decreased as required, and to prevent either the compression of air or the formation of a vacuum in the section 21 while these adjustments are being made, said section is provided with an appropriate vent 90 24. After adjusting the section 22, it may be held by any preferred means, such as a set-screw 25.

I have shown a cable 26 leading upwardly from the bucket 23 over a sheave 27 mounted 100 at the juncture of the braces 16 and tie-bars 17, said cable then extending inwardly over a sheave 28 on the pivot 20, from which sheave it depends to an appropriate drum 29 driven by an electric, pneumatic or other 105 motor 30 mounted on the support 18. By operating the drum 29, it will be seen that the cable 26 may be wound or payed out to raise and lower the bucket 23, and by means of the handle 11, the sleeve 7 may be turned 110 on the standard 1 to swing the boom 19 and associated parts, to any required position.

The bucket 23 may be provided with any suitable dumping bottom controlled by a hand rope 31 or any other suitable means.

All of the controls which are necessary for operating the machine are preferably located adjacent the motor support 18 so as to be readily within reach of the operator who may manipulate also the handle 11.

Thus, one man is enabled to rapidly load or 10 unload cars or the like and a great saving in time and labor is effected. Obviously, the length of the boom 19 may be increased or decreased as occasion may require, the set-screw 25 serving to hold the sections 21 and 15 22 against relative movement after the adjustment has been made.

The device is extremely simple and inexpensive, yet will be highly efficient and desirable and may be so constructed that by 20 merely removing a few bolts, the entire structure may be knocked down for easy carrying from place to place.

Since excellent results may be obtained from the details disclosed, they may well 25 be followed, but within the scope of the invention as claimed, numerous minor changes may be made.

I claim:

1. A device of the class described comprising a vertical standard having clamping screws at its upper and lower ends, a vertical sleeve rotatably surrounding said standard, a handle extending from said sleeve for turning the same, a load-raising boom pivoted to said sleeve, a frame structure supported by said sleeve and carrying cable guiding means, a hoisting cable for said boom trained over said cable guiding means, a motor support carried by said 30 frame structure and sleeve, a motor mounted 35

on said support, and a motor driven drum upon which said hoisting cable is wound.

2. A device of the class described comprising a vertical standard having clamping screws at its ends, a vertical sleeve rotatably surrounding said standard and supported thereby, a pair of brace bars secured at their lower ends to the lower end of said standard and inclining therefrom, tie-bars connecting the upper ends of said brace bars with the 45 upper end of said standard, a boom operable between said brace bars and pivoted to said sleeve, a sheave at the juncture of said brace bars and tie-bars, another sheave at the pivot of said boom, a hoisting cable 50 trained over said sheaves and connected with said boom, a horizontal motor support in the angle between said sleeve and said brace bars and jointly supported thereby, said brace bars diverging and straddling 55 said motor support, a motor mounted on said support, a drum driven by said motor and connected with said hoisting cable, and a handle extending from said sleeve for turning the same on said standard. 60

3. A device of the class described comprising a vertical standard and means for rigidly supporting the same, a vertical sleeve surrounding said standard rotatably and supported thereby, hoisting means carried by 70 said sleeve, a rigid handle extending laterally from said sleeve for turning it upon said standard, a latch associated with said handle and passing through said sleeve, and means carried by said standard to co-act 75 with said latch and hold said sleeve in adjusted position.

In testimony whereof I have hereunto set my hand.

GUSTAV CHRISTIAN NUSSSE.
